United States Patent Office

Des. 192,930
Patented May 29, 1962

192,930

ACTION TOY

Walter P. Doe, East Aurora, N.Y., assignor to Fisher-
Price Toys, Inc., East Aurora, N.Y., a corporation of
New York

Filed Mar. 6, 1961, Ser. No. 64,158

Term of patent 14 years

(Cl. D34—15)

FIG. 1

FIG. 1 is a top plan view of an action toy showing my new design.

FIG. 2 is a front elevational view thereof;

FIG. 3 is a side elevational view thereof, and
FIG. 4 is a rear elevational view thereof.

I claim:

The ornamental design for an action toy, substantially as shown.
